UNITED STATES PATENT OFFICE.

DOMINICK CORDINO, OF PLYMOUTH, MASSACHUSETTS.

METAL CASTING AND PROCESS OF MAKING METAL CASTINGS.

Application filed August 14, 1922. Serial No. 581,836.

To all whom it may concern:

Be it known that I, DOMINICK CORDINO, a citizen of the United States, residing at Plymouth, in the county of Plymouth and 5 State of Massachusetts, have invented new and useful Improvements in Metal Castings and Processes of Making Metal Castings, of which the following is a specification.

My invention relates to the method of 10 making metal castings, and the object of my invention is to dispense with drilling and tapping screw threads in castings of all kinds, and especially in gas, oil and other stove castings, in which the bolts and 15 fastenings are concealed on the face of the work.

My invention consists of an improvement 20 on the means of accomplishing the object described and claimed in my application for Letters Patent of the United States for process of making metal castings, Serial Number 508,512, filed October 18, 1921.

It is well known that in fastening panels to stove doors, and in securing together fixtures of various kinds in gas and oil stoves and other castings for the purpose of concealing the fastenings on the face of the work, it is customary to cast a lug or lugs on the inside of one casting and to drill 25 a hole in the lug and then tap a screw thread therein for the reception of a bolt or screw. These means are subject to a number of objections, and among them are: first, the danger of forcing the drill through the 30 casting and thereby destroying or defacing it; secondly, of breaking the tap by not judging the distance accurately and by driving it against the bottom of the hole. In some situations it is awkward to use the 35 drill and tap because of difficulty of access to the particular position of the lug, all of which accentuates the risk of forcing the drill through the casting and breaking the tap, and also makes accurate drilling and 40 tapping difficult, if not impossible.

My invention consists of a process of casting metal for the attainment of the foregoing objects, of certain novel devices to be employed in such process, and of the 45 article produced by the process.

In the accompanying drawing which illustrates some of the devices used in practicing my process, Fig. 1 is a perspective view of an attachment to the pattern used 50 in forming the mold; Fig. 2 is a perspective view of a chaplet incorporated into

the casting during the molding process; Fig. 3 is another perspective view of the chaplet and contents before casting; Fig. 4 is a plan view of a casting molded by 60 my process; Fig. 5 is a vertical section of one of the lugs 7 through the line X—X in Fig. 6, which is an enlarged perspective elevation of one of the lugs 7.

The first step in my process is to secure 65 to the pattern one or more attachments 16 like that shown in Fig. 1, made of any suitable material, preferably brass, the number and location of these attachments being governed by the requirements of the form 70 of a particular casting. These attachments are in the form of a socket to receive the chaplet 9. The upward extensions 13, 13^a, of the attachments 16 are of unequal heights; the extension 13^a being shorter 75 than the extension 13, so as to provide an opening in the cast lug for the reception of a nut into the chaplet.

Fig. 4 illustrates a casting 8 designed to have another casting or panel secured to it 80 at the four points indicated by the lugs 7. In molding such a casting as 8, there would be four of the attachments 16 secured to the pattern in the same relation, of course, to each other as the lugs 7, on the casting 85 shown in Fig. 4. Before making the mold, a chaplet 9, shown in Fig. 2, made of sheet metal or other suitable material, is inserted in each attachment 16 on the pattern. The upper portion of the chaplet is filled with 90 a core 11, as shown in Fig. 3, capable of becoming disintegrated by the molten metal, but remaining intact during the molding process sufficiently to prevent being displaced by the pouring of the metal. Below 95 the core 11 is a narrow space 12 as shown in Fig. 3. The chaplet containing the core 11 is inserted in the attachment 16 in the pattern, with its open ends adjacent to the upright portions 13, 13^a of the attachment 100 16, whereby the molding sand cannot enter the space 12 in the chaplet 9, during the making of the mold. The pattern is then placed in the molding sand in the usual manner for casting with the attachments 16 105 on the upper side of the pattern, and when the cope is raised from the drag, the chaplet 9 being light and loosely resting in the attachment 16, is lifted by the cope to which it adheres. The pattern is then removed 110 from the drag, the cope is closed and the metal poured in the usual manner. By rea-

son of the extension 13^a of the attachment 16 being shorter than the extension 13, and not reaching to the top of the chaplet, the cast lug is open at the top on the side corresponding to the extension 13^a. The result is that lugs like the lug 7 are cast, in which the space 12 in the chaplet 9 is filled with metal which flows into the chaplet through the opening 17, and the core 11 is so disintegrated by heat that it is readily removed when the castings are rattled, leaving the upper portion of the chaplet 9, and the hole 18 therein open. The space left in the upper portion of the chaplet by the disappearance of the core is sufficient to admit a screw threaded nut 10 in the top, and to leave an open space below it and above the metal 19 which forms the bottom of the chaplet after casting, as shown in Fig. 5. In Fig. 6 is shown the nut 10 inserted in the chaplet 9. The chaplet 9 is flaring at the top for the purpose of receiving the nut 10 and forming shoulders for supporting the nut 10 so as to leave the open space 14 below it. After the casting is made, a nut 10 of suitable size and having a screw threaded hole properly located to coincide with the hole 18 in the chaplet 9, is inserted into the top of the chaplet. It is desirable to have the nut fit snugly so as not to become easily displaced. This arrangement permits of the removal of the nut at any time, if desired, and replacement of a new one for the purpose of making repairs.

Referring to the casting 8 in Fig. 4, each of the lugs is provided with a screw threaded hole 18 in its top to receive a screw or bolt 15 for the purpose of securing another casting thereto. It is obvious that by this method of casting, the holes in the lugs are accurately located, that all danger of defacing the casting by accidentally drilling through it is obviated, and as no tapping of the thread is required, there can be no breakage of taps. The screws or bolts employed are selected with reference to their length, so as not to extend to the bottom of the space 14 shown in Fig. 5. The screws or bolts are readily removed when occasion requires separation of the casting for repairs or other purposes.

The provision of the open space below the nut in the construction shown in the pending application, as well as in this application, is of great importance in case it becomes necessary to remove the bolts or screws for the purpose of repairs for the reason that the end of the screw or bolt is

free from contact with the casting, and therefore does not become adhered thereto by reason of corrosion. Where no such space is provided it is often impossible to remove the bolt when desired without breaking it or destroying the casting or requiring drilling and tapping of the lug.

In my pending application above referred to, I have shown and described a nut inserted in the chaplet before the casting is made and thereby fused into the lug or having the top of the chaplet itself sufficiently thick to admit of tapping a screw threaded hole therein and dispensing with the use of a separate nut, from each of which methods the present invention is distinguished. While having all the advantages of the former it has the additional advantage that nuts of different sizes may be selected for insertion into the lugs, and the nuts may be removed at any time for replacement when needed for repairs.

What I claim and desire to secure by Letters Patent is:

1. The hereinbefore described process of casting metals consisting of forming a mold having a chaplet incorporated therein, said chaplet having openings on two sides, and having its upper portion filled with a core, and having a chamber located beneath the core, said mold being formed so as to permit one of said openings to be closed and the other to be partially closed with the molten metal, then pouring the molten metal into said mold and thereby filling said chamber and closing one of said openings and partially closing the other, whereby the casting is provided with a chamber closed at the bottom and with a side opening near the top adapted to receive a screw threaded nut.

2. In a metal casting a chaplet having a chamber therein and having no opening in its bottom through the casting, said chaplet being adapted to receive and removably support a screw threaded nut in the upper part of said chamber.

3. In a metal casting a chaplet having a screw threaded nut removably located in its top, combined with a chamber located beneath the nut and having no opening in its bottom through the casting.

In testimony whereof I have hereunto set my hand in presence of two subscribing witnesses, this eighth day of August, 1922.

DOMINICK CORDINO.
